UNITED STATES PATENT OFFICE.

HUGH L. GADDIS, OF MACOMB, ILLINOIS, ASSIGNOR TO AMERICAN STEEL PRODUCTS CO., OF MACOMB, ILLINOIS, A CORPORATION OF ILLINOIS.

SLOW-BURNING STOVE.

Application filed May 10, 1924. Serial No. 712,230.

To all whom it may concern:

Be it known that I, HUGH L. GADDIS, citizen of the United States, residing at Macomb, in the county of McDonough and 5 State of Illinois, have invented certain new and useful Improvements in a Slow-Burning Stove; and I do hereby declare the following to be a full, clear, and exact description of the invention, such as will enable 10 others skilled in the art to which it appertains to make and use the same.

My invention relates to stoves or heaters and in its general objects aims to provide a stove construction which will increase the 15 lateral radiation of heat by compelling the products of combustion to pass close to the lateral wall portions of the stove before they can reach the flue, which will retard the flue draft so as to effect slow combustion 20 of a fuel which otherwise would burn rapidly, and which will afford ready means for catching and removing the flue drip encountered when certain kinds of fuel are burnt at a relatively slow rate. Furthermore, 25 my invention provides a stove or heater construction in which a single and simple member will readily afford all of the above named objects, in which the said member can readily be removed from the stove and 30 replaced therein, in which the regular fuel door of the stove will afford access to the said member, and in which the said member will also be disposed in an advantageous position with respect to the check draft used 35 for controlling the operation of the stove.

In employing coal burning heaters for such purposes as the warming of the space under the hover or hood of a brooder, the intense heat produced by burning ordinary 40 coal after the manner generally customary with stoves employed in households would produce a highly excessive temperature, hence it is necessary to restrict the draft of such a stove so as to cause the fuel to be 45 consumed at a much lower rate. It is also highly desirable that the heat should be radiated to a large extent laterally of the stove rather than upwards, for which reason it is important that the hot gases should 50 pass close to the lateral walls of the stove instead of moving practically vertically towards a flue outlet in the top of the stove. My present invention affords a simple and effective construction for this purpose by

providing a baffle constructed for compelling the hot gases to pass close to opposed walls of the stove before they can reach the flue, and by restricting the openings between the combustion chamber of the stove and the flue so as to retard the normal draft 60 of the stove to a suitable extent.

Moreover, when common fuels, such as cheap grades of soft coal, are consumed at the relatively low rate resulting from such a restriction of the stove draft, many of the constituents of the fuel are not entirely consumed. Instead, they are merely distilled off and rise past the baffle in the form of unburnt vapors. When these vapors strike the relatively cool flue pipe, they are 70 condensed on the interior of the latter and the resulting condensed distillate trickles down and deposits itself in the form of a tarry and sticky mass on any ledge below the flue pipe, such as would be formed by 75 such a baffle. If the resulting accumulation is not occasionally removed, the continued depositing of the same will gradually clog the openings adjacent to the baffle, thereby seriously interfering with the normal draft 80 and the proper operation of the stove. To guard against such occurrences, my invention provides a stove construction in which the drip catching baffle is removably supported within the stove, and provides a 85 stove with a door through which the baffle can be readily withdrawn for removing the said accumulated flue drip. Furthermore, my invention desirably provides a stove construction in which the fuel door will afford 90 the needed access to such a fuel-drip catching member.

In a still further aspect, my invention provides a stove construction which will permit such a removable flue-drip catching 95 baffle to be employed advantageously in connection with the automatically operating check draft arrangement disclosed in my copending application #712,229, filed May 10, 1924 on a brooder stove, and provides 100 a simple stove construction for this purpose in which the said combination baffle and flue-drip catching member affords part of a flue chamber and is disposed so that the check draft air will pass over the top of the baffle and over the drip which may have accumulated on the latter. Still further and also more detailed objects will appear 105

from the following specification and from the accompanying drawings, in which

Fig. 1 is a central, vertical and longitudinal section through a heating stove embodying my invention.

Fig. 2 is a horizontal section taken through Fig. 1 along the line 2—2 and looking upwards.

Fig. 3 is an enlarged perspective view of 10 the combined baffle and flue-drip catching member.

Fig. 4 is a fragmentary section of the 15 upper portion of another embodiment of my invention, namely one constructed without a check draft duct and having a hinged door in the top of the stove for affording access to the combined baffle and flue-drip catching member.

Fig. 5 is a section similar to Fig. 3, but 20 showing an embodiment in which the effective riser wall of the baffle is carried by the door.

Fig. 6 is a similar section through another embodiment, namely one in which the 25 door is in the front wall of the stove.

Referring first to the preferred embodiment of Fig. 1, this shows a stove having its main portions composed of three superposed sections, namely a base 1 having a top 2 which affords the bottom of the firebox, a firebox section 3 having rocking grates 4 supported by it, and a combustion chamber section 5. This combustion chamber section is provided adjacent to its top with an inwardly projecting ledge 6 extending at least along two opposite sides of this stove and affording a support for the detachable member of the stove. Supported by the top of the said combustion chamber section of the 30 stove is a top portion 7, here shown as arched upwards to provide a sufficient height above the ledge 6 for affording a flue chamber between the bottom of the said detachable member and the flue collar 8 which carries the usual sheet metal flue pipe. This 35 top portion of the stove has a relatively large opening which can be employed for feeding fuel to the stove and which normally is closed by a removable door 9.

Supported by the said ledges 6 is the removable member of my stove, which in the embodiments of Figs. 1 to 3 comprises two portions, namely a riser wall 12 extending along the front of the flue collar substantially from one side wall of the stove to the other as shown in Fig. 2, and a bottom 13 which is recessed adjacent to each side wall of the stove so as to afford passages 10 operatively connecting the combustion chamber 40 of the stove with the flue. For this purpose, I am here showing the said removable member as having its riser portion 12 formed integral with its bottom portion 13, and I also desirably provide a suitable handle 14 on the forward face of the riser

whereby this member may be grasped for removing it through the fuel feed opening in the top of the stove after the door 9 has been detached.

In employing such a stove for purposes 70 where a control of the temperature is highly important, I desirably provide a by-pass duct 15 leading from the ashpit of the stove to the space between the bottom of the flue collar and the top of the plate 13 which 75 forms the bottom of the baffle and also provide a rocking damper 16 in the said duct, whereby the flow of air through this duct can be controlled automatically after the manner disclosed in my said copending 80 application.

With the heating stove thus constructed, it will be obvious from the drawings that the gaseous products of combustion cannot move in straight lines towards the flue, but 85 can only reach the latter after passing through the said connecting passages 10 adjacent to the opposite lateral edges of the baffle bottom 13. Consequently, these products of combustion are compelled to pass 90 close to the two side walls of the stove, thereby increasing the lateral radiation of heat. It will also be evident that any drip from the flue due to the condensing of unburnt distillate on the relatively cool flue 95 portions will flow down upon the bottom 13 of the baffle, so that the resulting accumulation can readily be removed at suitable intervals by simply withdrawing this baffle member from the stove through the door 100 opening and scraping off the accumulated deposit. However, since the baffle bottom 13 is effectively heated during the normal operation of the stove, the drip caught on the latter is also maintained at a fairly high 105 temperature, so that some of this may be entirely consumed by air passing over the baffle both through the said passages 10 and through the by-pass duct 15.

By placing the ledge 6 substantially at the 110 top of the casting which houses the combustion chamber 11 of the stove, I simplify the casting operation, and since the said ledge will also tend to deflect upwardly moving gases towards the interior of the stove, this ledge also cooperates in compelling the 115 said gases to flow along paths which will increase the lateral radiating effect of the stove.

However, while I have heretofore described my invention in a highly desirable embodiment particularly suited for use in connection with brooders, I do not wish to be limited to this use of the same, as my invention obviously could be employed also 120 to good advantage in stoves employed for other purposes. Neither do I wish to be limited to the use of my invention in connection with a stove having a check draft 125 duct leading to the space above the baffle, 130

or to other details of the construction and arrangement above described. Obviously, these might all be varied in many ways without departing either from the spirit of my invention or from the appended claims.

For example, Fig. 4 shows my invention as applied to a stove having a hinged door in its top and having the removable member supported on relatively short ledges. Fig. 5 also shows an inclined door 18 at the top of the stove, but shows this as bodily detachable and as carrying a downwardly extending riser wall 19 which cooperates with a simple horizontal baffle plate 20 in affording the same general effect as that obtained by making the baffle bottom 13 and the riser wall 12 integral with each other after the manner of Figs. 1 to 4 inclusive. That is to say, the flue chamber 21 between the flue collar 8 and the baffle bottom 20 (which flue chamber effectively forms the lower part of the flue considered as a whole) in this instance has its front and rear walls formed respectively by the depending portion 19 of the door and by the rear wall 22 of the stove, leaving only the horizontal baffle 20 to deflect and throttle the products of combustion and to catch the flue drip. So also, the door and the opening for the same need not be in the top of the stove, but such a door 23 might be in the front wall, as shown for example in Fig. 6.

I claim as my invention:

1. The combination with a stove having a flue outlet in its top, of a flue-drip catching member removably supported below the flue outlet, and a door disposed so that the said member can be removed and reinserted through it.

2. The combination with a stove having a flue outlet in its top, of a flue-drip catching member removably supported below the flue outlet, and a door disposed so that the said member can be removed and reinserted through it, the said member being shaped to afford a baffle for causing the combustion products to pass close to wall portions of the stove before they can reach the flue outlet.

3. The combination with a stove having a flue outlet in its top, of a flue-drip catching member removably supported below the flue outlet, and a fuel feed door disposed so that the said member can be removed and reinserted through the door.

4. The combination with a stove having a flue outlet in its top, of a flue-drip catching member disposed within the body of the stove and having a substantially horizontal portion under the flue outlet, and a door through which the said member may be manually withdrawn and inserted.

5. The combination with a stove having a flue outlet in its top, of a flue-drip catching member disposed within the body of the stove and having a substantially horizontal

portion under the flue outlet, and a door through which the said member may be manually withdrawn and inserted, the door having its lower edge at approximately the same height as the horizontal portion of the said member so as to permit the removal of the said member without a material tilting thereof.

6. A stove having its body provided with supporting ledges spaced from its top, a baffle removably supported on the said ledges and having a substantially horizontal bottom, the stove having a flue outlet disposed over and spaced vertically from the said baffle bottom so that the latter will catch drip from the flue, the body having an opening through which the baffle plate can be withdrawn, and a door normally closing the said opening.

7. The combination with a stove body having a flue outlet in its top, of a baffle removably supported within the body and having a riser portion extending substantially across the interior of the stove body, the baffle also having a bottom with an imperforate portion disposed vertically below and spaced from the flue outlet and with opposed edge portions spaced from the adjacent side walls of the stove to permit products of combustion to pass between the said edge portions and the said walls.

8. A stove having its body provided with supporting ledges spaced from its top, a baffle plate removably supported on the said ledges and formed to provide apertures adjacent to opposed walls of the stove, the stove having a flue outlet disposed over and spaced vertically from the baffle plate so that the latter will catch drip from the flue, the body having an opening through which the baffle plate can be withdrawn, a door normally closing the said opening, and a vertical plate disposed between the said baffle plate and the flue outlet at one side of the latter and cooperating with the baffle plate for affording a flue chamber within the stove.

9. A stove having an opening in one portion of its top and having another part of its top relatively higher and provided with an upper flue outlet, a baffle plate removably supported within the stove under the flue outlet and at a height approximating that of the first named top portion of the stove, the baffle plate being of such a size as to permit its removal through the said opening, and a door normally closing the said opening.

10. A stove having an opening in one portion of its top and having another part of its top relatively higher and provided with an upper flue outlet, a baffle removably supported within the stove under the flue outlet and having a substantially horizontal portion disposed at a height approximating

that of the first named top portion of the stove, the baffle being of such a size as to permit its removal through the said opening, and a door normally closing the said opening, the baffle also having an integral riser portion extending upward close to the flue outlet at one side of the latter.

11. A stove having its body provided with supporting ledges spaced from its top, a baffle removably supported on the said ledges and having a substantially horizontal portion, the stove having a flue outlet disposed over and spaced vertically from the said baffle portion so that this portion will catch drip from the flue, the body having an opening through which the baffle plate can be withdrawn, a door normally closing the said opening, and a duct for supplying air to the interior of the stove body above the said portion of the baffle to facilitate the combustion of the drip caught by the said baffle portion.

12. A stove having its body provided with an upper flue outlet, a baffle removably supported within the body and having a bottom vertically below the said outlet and spaced from the latter, a door normally closing the said opening, the baffle plate having its said bottom forming part of the top of the combustion chamber of the stove, and a duct for admitting air from outside the combustion chamber of the stove to the space between the said baffle bottom and the flue outlet.

13. In a stove, a body having a flue outlet in its top, a baffle supported within the body

and having a bottom portion vertically below the said outlet and spaced from the latter, the baffle being so shaped as to afford a flue chamber below the said outlet, and a duct leading from the ashpit of the stove to the flue to the said flue chamber.

14. A stove as per claim 13, in combination with means for controlling the passage of air through the duct.

15. A stove as per claim 13 in which the duct has a wall portion disposed for being heated by the direct conduction of heat from a wall of the stove.

16. A stove body having one part of its top closed except for a recess extending to one wall of the body and having a riser extending upwardly along the edge of the recess which is away from that wall, an ashpit below the body and having an opening under the said wall, a duct casting secured to the said wall and cooperating with the latter to form an air duct leading from the ash pit to the portion of the stove above the said recess and overhanging the said recessed portion of the top, the said riser and the duct casting having adjoined upper portions cooperating to form a flue outlet for the stove, and a baffle detachably supported by the stove body and extending both under the flue outlet and under the overhanging portion of the duct.

Signed at Macomb, Illinois, April 30, 1924.

HUGH L. GADDIS.
